UNITED STATES PATENT OFFICE.

HARVEY A. PINEGAR, OF WELLINGTON, UTAH.

BOLT AND NUT LOCK.

1,114,381.

Specification of Letters Patent.

Patented Oct. 20, 1914.

Application filed October 14, 1913. Serial No. 795,051.

To all whom it may concern:

Be it known that I, HARVEY A. PINEGAR, citizen of the United States, residing at Wellington, in the county of Carbon and 5 State of Utah, have invented certain new and useful Improvements in Bolt and Nut Locks, of which the following is a specification.

This invention relates to improvements in 10 devices for preventing the retrograde movement of nuts on bolts, more particularly to bolts employed in connection with the main trace supporting portions of the hames of a harness, and has for one of its objects to 15 simplify the construction and improve the efficiency and utility of devices of this character.

With these and other objects in view the invention consists in certain novel features 20 of construction as hereinafter shown and described and then specifically pointed out in the claims, and in the drawings illustrative of the preferred embodiment of the invention Figure 1 is a perspective view of a 25 portion of a conventional hame with the improvement applied. Fig. 2 is a detached perspective view of the bolt holding member.

Corresponding and like parts are referred to in the following description and indicated in all the views of the drawing by the same reference characters.

Much annoyance and difficulty have been heretofore experienced from the tendency 35 of the rods which hold the main trace supporting member upon a hame working loose under the jarring strains to which they are subjected, and the principal object of the present invention is to provide a simply constructed attachment whereby the rods of devices of this character are locked in position and prevented from retrograde movement, and in the drawings in Fig. 1 the improved device is shown applied to a rod of 40 this character, the body portion of the hame being represented conventionally at 10 and the metal supporting plate at 11 of the usual construction. Extending from the 45 body portion of the hame and operating through the metal portion 11 are standards 50

12—13 spaced apart, the standard 13 having a threaded aperture to receive the threaded terminal 14 of a rod 15, the latter extending at one end through the standard 12 and provided with a head 16 preferably square as shown. Bearing upon the member 11 adjacent to the standard 12 is a holding member including a base 20 and a lateral offset 21, the latter engaging one face of the square head 16, while the base 20 is secured to the member 11 by a suitable fastening device 65 such as a screw 22. After the rod 15 has been turned "home" by a wrench applied to its head, the holding member 20 is arranged in position with its offset 21 against the head 16 and the fastening device 22 applied. By this means it will be obvious that a simply constructed holding device is produced which bears against the head 16 and prevents any retrograde movement of the rod. By this means also the rod is retained 70 in position within the standards and all tendency to work loose or become detached is effectually prevented.

The improved device is simple in construction, can be inexpensively manufactured and applied, and does not detract from the appearance of the harness and does not require any change in the construction of the parts except to form an aperture in the member 11 to receive the fastening device 80 22 which is threaded to engage in the body 85 10 of the hame.

Having thus described the invention, what is claimed as new is:

1. The combination with a supporting body, of a standard having a threaded aperture, a threaded member engaging said threaded aperture and provided with a head including a flat face, a holding member bearing upon the supporting body and formed 90 with an offset engaging against the flat face of the head, and fastening means connecting the holding member to the supporting body.

2. The combination with a supporting body, of perforated standards spaced apart 100 and extending from the body, one of said standards having its perforation threaded, a member threaded at one end to engage the threaded aperture of the standard and hav-

ing a polygonal head bearing against the other standard, a holding member bearing upon said supporting body and provided with an offset engaging the head of the 5 threaded member, and fastening means operating to secure the holding member to the supporting body.

In testimony whereof I affix my signature in presence of two witnesses.

HARVEY A. PINEGAR. [L. S.]
